UNITED STATES PATENT OFFICE

160,147

COMBINED PURSE, KEY HOLDER, AND CONTAINER FOR PHOTOGRAPHS OR THE LIKE

Herbert S. Chase, New York, N. Y.

Application March 10, 1950, Serial No. 8,452

Term of patent 14 years

(Cl. D87—3)

To all whom it may concern:

Be it known that I, Herbert S. Chase, a citizen of the United States of America, residing in New York city, county of New York, and State of New York, have invented a new, original, and ornamental Design for a Combined Purse, Key Holder, and Container for Photographs or the like, of which the following is a specification, reference being had to the accompanying drawing, forming part thereof, wherein:

Figure 1 is a front elevational view of a combined purse, key holder and container for photographs or the like embodying my new design.

Figures 2 and 3 are rear and side elevational views, respectively, of the article, and

Figure 4 is a plan view on a reduced scale illustrating the inside of the article.

I claim:

The ornamental design for a combined purse, key holder, and container for photographs or the like, substantially as shown.

HERBERT S. CHASE.
